DELAYED ARMING MECHANISM

Parke H. Thompson, Kirkwood, Mo., assignor to
 United States of America as represented by the
 Secretary of the Army

Application January 8, 1952, Serial No. 265,444

15 Claims. (Cl. 102—79)

1

The present invention relates to a delay arming device for a projectile fuse.

The use of delay arming devices in fuses for explosive and incendiary projectiles are well known in the art. Such delay arming devices are provided to maintain the fuse safely unarmed while the projectile is traversing the bore of the weapon, and for a predetermined time thereafter to prevent premature explosions which would endanger the lives of operating personnel in the gun crew, and could also lead to the destruction of the weapon from which the projectile is fired. In addition premature explosions would also endanger friendly personnel in forward battery positions and would obviously render considerably less effective the striking force of an attacking unit due to the decrease in the number of projectiles exploding upon the selected target. Delay arming devices of the kind found in the prior art usually involve mechanism which is armed by means responsive to rotation of a projectile or to linear acceleration of a non-rotating projectile, as for example arming blocks movable into position by linearly or centrifugally responsive gear trains, centrifugal arming ball rotors etc.

It is accordingly a specific object of this invention to provide a delay arming device for a fuse which maintains the fuse elements in unarmed position for a predetermined interval of time sufficient to permit the projectile to clear the gun, and to travel to a safe location.

A more specific object of this invention is to provide a delay arming device for a rotating projectile including an arming ball rotor which is movable into armed position by mechanical means actuated by a centrifugally responsive substantially toroidal expansible spring.

Another object of this invention is a similar delay arming device for a non-rotating projectile wherein the toroidal spring is torque loaded or prestressed as by winding, in order to move the arming ball rotor into armed position upon release of the spring by means responsive to linear acceleration.

Another further object of this invention is to provide a delay arming mechanism in a fuse, including a housing and cover having allochirally mated concavities to complete a spheroidal cavity for receiving a metal ball rotor, wherein means are provided in the cover to engage and move the ball rotor into armed position under the action of a substantially toroidal spring which is joined at opposite ends to the cover and to the main fuse body.

With these and other objects in view which will appear as the following specification develops, reference is made to the accompanying drawing wherein like numerals are used to desig-

2

nate corresponding or similar parts in the several views and wherein:

Figure 1 is a longitudinal section of the fuse body with the metal ball rotor and movable parts in unarmed position.

Figure 2 is a fragmentary section similar to Figure 1 but with the ball rotor and moving parts in armed position.

Figure 3 is a view showing respectively, from left to right, the housing and concavity, the metal ball rotor, and the cover with mating concavity.

Figure 4 is a transverse section taken on line 4—4 of Figure 2.

15 Figure 5 is a section looking in the direction of arrows 5—5 of Figure 2 and showing details of the escapement lever or pawl.

20 Figure 6 is a section looking in the direction of arrows 6—6 of Figure 2, and showing details of the cover including the interdental spaces which coact with the pallets on the escapement pawl.

25 Figure 7 is a longitudinal section of a modification of the delay arming device (assembled), wherein the escapement pawl and associated parts are located within the housing.

Figure 8 is a section taken on line 8—8 of Figure 7.

30 Figure 9 is a view on line 9—9 of Figure 8 looking in the direction of the arrows.

Figure 10 is a view on line 10—10 of Figure 8 looking in the direction of the arrows.

35 Referring more particularly to Figures 1 and 2, 1 designates the main body of the projectile of the point-detonating type, peripherally recessed at 2 to accommodate the nose portion 3 to complete the forward ogive of the projectile. The main body portion 1 has an axial bore 4 which is stepped as at 5 and enlarges rearwardly into a counterbore 6 which forms the main explosive or incendiary charge container, as is well known, to receive a charge 7. A cup-shaped member 8 is press fitted into bore 4, a portion of this cup extending rearwardly into counterbore 6, as at 9, to serve as a container for receiving a booster charge 10.

40 The delay arming device per se comprises a cylindrical core 11, which is shaped like an E in cross section to form an annular chamber 12 between the legs and central portion thereof. Core 11 is tightly press fitted into cup-member 8 with its rearward face spaced from the bottom of the cup member 8 to form the before-mentioned booster charge receiving space 9. An axial counterbore 13 is formed in the central portion of core 11 to serve as a housing 11a for an arming ball rotor 14, the central portion of the rear wall of counterbore 13 being dished out as at 15 to form a spherical cavity upon which is seated for rotation thereon the rotor 14. Spherical cavity 15 is centrally apertured as 16

60

communicate with an axial bore 17 formed in core 11, which may be either an unobstructed passage extending between counterbore and booster container 9, or as seen in Figures 1 and 2, may receive a capsule 18 which contains a detonating substance 19. A pivot pin 5 is made integral with housing 11a and extends partly into counterbore 13, and when the 10 device is assembled, also is received in a drilled cavity 21 in rotor 14 to enable rotor 14 to pivot about an axis which is normal to the longitudinal axis of the projectile and in a plane of motion normal to the plane of motion of the cover (see figures 2 and 3). Rotor 14 is provided with a diametral bore 22 for receiving a capsule 23 containing a detonating substance 24, and in unarmed position (Figure 1) the axis of bore 22 is crosswise of the longitudinal axis of the projectile.

A cap or cover 25 having a rearwardly directed flange 26 is fitted about and slidably engages the outer surface of the central forwardly extending portion of housing 11a. Cover 25 is provided with a dished out central concavity 27, to form a spherical seat for rotor 14, which is allochirally seated with seat 15 in housing 11 to complete the hemispherical cavity in which rotor 14 rotates. A setting pin 28 is made integral with cover 25 and extends into an arcuate peripheral slot 29 in rotor 14. When the fuse is assembled, the arcuate contour of the slot being such that when the cover 25 is rotated through an angle of 180 degrees, rotor 14 pivots about pin 28 and turns through an angle of 90 degrees in a plane of motion normal to the plane of motion of the cover, so that the axis of the detonating capsule 23 and the longitudinal axis of the projectile will be aligned to arm the fuse. As the cover rotates one quarter turn the setting pin traverses the entire length of the rotor 14, and moves back to its original position in the slot during the second quarter turn.

A toroidal expansible member is provided to rotate cover or cap 25, and in the present instance comprises substantially toroidal power spring 30 imbedded in chamber 12 tightly fitting about cover 25; when the fuse is unarmed and making approximately $1\frac{1}{4}$ turns about the cover with one end secured by any convenient manner, as by hook and eye pad, to cap 25 (see Figure 4), and the other end secured in like manner as at 32 to the inner wall of chamber 12 formed by rotor housing 14. Spring 30 in unarmed position is unstressed and exerts no torque, therefore the fuse will remain unarmed if the projectile is accidentally dropped, and under ordinary conditions of handling. However when the projectile is fired and caused to rotate by the means provided for that purpose, spring 30 will expand and, since end 32 is anchored, will cause cover 25 to rotate, and all rotor 14 to move into armed position by virtue of the pressure applied to the rotor by setting pin 28 within the confines of slot 29.

The delay arming device is also provided with escapement means to cooperate with the power spring in order to insure timed motion for arming the rotor. This escapement means comprises the expedient of beveling the peripheral forward surface of the cap 25 as at 33 and forming therein serrations 34 which function as gear teeth to engage the pallets 35 of an escapement lever 36. An odd number of serrations is provided in order that oscillation of the escapement will occur, wherefore one pallet will move toward engagement while the other progresses toward release.

The escapement lever 36, as seen in Figure 5, 75

is a substantially cylindrical metal member of relatively massive weight wherein the pallets 35 are simple pyramidal bosses spaced 180° apart and having apices directed radially inward, such that mating engagement occurs with the interdental spaces along the serrated bevel of the rotor cover. The lever is provided with diametrically opposed pivots 37, journaled in bearing holes 38 in core 11, with the axis of the pivot points normal to, and coplanar with the axis of the pallets.

Cap 25 and escapement lever 36 are provided with centrally disposed axially aligned bores 39 and 40 respectively, which will also align with the diametral bore 22 in rotor 14 when the rotor 15 is in armed position. Bores 39 and 40 together serve as a flash passage to ignite the detonating capsule in the rotor, if the fuse is flash initiated, or, if stab initiation is contemplated, a firing pin (not shown) may be mounted therein with a rearwardly directed point to contact and explode the detonator in the rotor, when the fuse is armed and impact occurs.

Figures 7-10 relate to a modification wherein the arrangement of parts is more compact, and wherein the escapement pawl and associated parts are located within the inclosed housing rather than externally as in the species of Figures 1-6.

Referring to Figures 7-10 wherein the same numerals primed have been used to designate corresponding or similar parts, 11a is the main housing of the device, which for purposes of illustration, is seen as a cylindrical member having an axial counterbore 13' to receive the escapement pawl and arming ball rotor 14'. The central portion of the rear wall of counterbore 13' is dished out as at 15' to form a spherical cavity to seat for rotation, the arming ball rotor 14'. Cavity 15' is centrally apertured at 16' to communicate with a flash passage in the fuse body, similarly as in Figures 1-6.

As previously explained, the escapement pawl or lever 36' is received within housing 11a, and comprises a cylindrical member of relatively massive weight with its forward and rearward faces tapering slightly from relatively thin portions 36a spaced apart 180° to thicker portions 36b on an axis normal to a line through the thinner portion of the pawl. This configuration enables the pawl to rock back and forth when engaging a flat surface, and the pawl is located in counterbore 13' so that its rear face engages the flat bottom wall of the counterbore which surrounds spherical cavity 15'. The forward face of the escapement pawl is provided with a pair of pallets 35' 180° apart, and at a location coinciding with the axis through thinner portions 36a of the lever. The pawl 36' is provided with a bore 36c which is substantially axially cylindrical, but which is provided with flat surfaces 36d normal to the axis upon which the lever rocks. In like manner arming ball rotor, though substantially spherical is also provided with flat sides 14a having outstanding protuberances or pins 14b which are journaled in longitudinal slots 36e formed in flat surfaces 36d so that the arming ball rotor is free to rotate in bore 36c on a diametral axis through the pins 14b. Additionally, the arming ball rotor is provided with diametral bores 22a and 22b which are normal to each other and to the axis of rotation of the ball, so as to extend between spherical surfaces of the ball rotor. One of the bores is provided with a detonator 24', the axis of which in unarmed position of the fuse, lies cross-wise of the longitudinal axis of the device.

In order to prevent the escapement lever from turning relative to housing 11a, there is provided a forwardly directed pin 11b made integral with housing 11a and extending from the bottom wall of counterbore 13' into a longitudinal bore 36f in escapement pawl 36', when the device is assembled.

The delay arming device is provided with a cover 25' which has a rearwardly reduced portion to fit into and slidably engage the inner wall of counterbore 13'. The cover is provided with a counterbore 25b opening rearwardly into counterbore 13' and the forward wall of counterbore 25b is dished out centrally as at 27' to form a spherical seat, for rotor 14', allochirally mated with seat 15' in housing 11a, and which with seat 15' and cylindrical bore 36c in the escapement pawl completes the substantially spheroidal cavity in which arming ball rotor 14' rotates.

The escapement means for this modification is similar in action to the one provided for the species illustrated by Figures 1-6, but is slightly different in design. The pallets 35' on the forward face of the escapement pawl, instead of being pyramidal, are semi-spherical bosses spaced 180° apart, on an axis normal to the axis upon which the pawl rocks. The rearward flat surface of the cover is provided with a plurality of closely spaced equiangularly disposed semi-spherical holes 34' axially concentric with respect to the cover per se, and which are perimetrically engaged by the pallets as the lever oscillates and the cover rotates.

An odd number of holes are provided in the cover, so that coaction between the spherical bosses and spherical cavities is the same as that between the pyramidal pallets and gear teeth of the first described species, wherefore one pallet will move toward engagement while the other progresses toward release. Movement of the cover, similarly, is provided by a coil spring (not shown) surrounding the cover, which is expandable in response to centrifugal force or which may be prestressed as by winding the cover, to turn the cover when it is released by linear acceleration or deceleration. The cover is also provided with a setting pin 28' made integral therewith and extending rearwardly and inwardly into an arcuate peripheral slot 29' in arming ball rotor 14'. As previously explained the contour of the slot is such that as the cover rotates through an angle of 180 degrees about the longitudinal axis of the device, arming ball rotor 14' rotates, as a result of the pressure applied by the setting pin, through an angle of 90 degrees in a plane of motion normal to the plane of motion of the cover, to place the axis of detonating capsule 24' in coincidence with the longitudinal axis of the device, to thereby arm the fuse.

Operation

Driving torque is supplied by coil power spring 30. While the projectile is at rest the spring, being unstressed, exerts no torque. When the projectile is fired and is caused to rotate by the means provided for that purpose, spring 30 is expanded by centrifugal force, moving outward in chamber 12 from its initial position against rotor cover 25 until it seats against the cylindrical surface of chamber 12. In this position the spring exerts a torque on the rotor cover causing it to rotate through an angular displacement of 180° within an interval of time determined by the oscillating characteristics of the escapement lever. The lever will rock on its pivots so that

one pallet moves toward engagement while the other pallet progresses toward release. The motion of rotation is transmitted from the rotor cover to the rotor through the setting pin and arcuate slot, and the rotor is brought to armed position in the manner previously described.

It is within the scope of this invention to also make the delayed arming mechanism and escapement means, above described, applicable to a non-rotating projectile. In this modification some well known winding means may be associated with the cover to turn it a predetermined amount to prestress the coil spring. A release will be provided which may be a pin mounted in the fuse body and effective to engage and lock the cover after winding, so that the ball rotor is in unarmed position. In response either to linear acceleration or deceleration, the pin will release the cover so that the prestressed spring will cause it to rotate. The escapement lever will act similarly as above described, while the rotor is being moved into armed position.

Other modifications and alterations of the structure which has been disclosed herein for purposes of illustration will be apparent to those skilled in the art, and it is obvious that the same may be made without departing from the spirit and scope of the invention as defined in the following claims.

30 I claim:

1. A delay arming device for projectile fuses comprising, a housing having an axial counterbore, an arming ball rotor in said counterbore rotatable from first unarmed position to second armed position and having an arcuate peripheral slot, a cover for said housing, a setting pin integral with said cover extending into said rotor slot, means to turn said cover relative to said housing whereby said pin rotates said ball rotor, and escapement means associated with said cover to provide timed motion for arming said ball rotor.

2. The combination in claim 1 wherein said means to turn said cover comprises an expandable member having one end secured to said housing and a second end secured to said cover.

45 3. The combination in claim 2 wherein said expandable member expands in response to centrifugal force to turn said cover.

4. The combination in claim 3 wherein said escapement means includes a peripheral bevel formed in the forward surface of said cover, a plurality of serrations formed in said beveled surface, an escapement lever pivotally mounted in said housing and having a rearward surface adjacent to and substantially parallel with the forward surface of said cover, and a plurality of pallets on said escapement lever surface interdigitally engaging said serrations.

5. A delay arming device for a rotating projectile fuse comprising a housing, an arming ball rotor in said housing rotatable from first unarmed position to second armed position and having an arcuate peripheral slot, a cover for housing, a setting pin integral with said cover and extending into said peripheral slot, means responsive to centrifugal force to turn said cover relative to said housing and said rotor relative to said cover, and escapement means in said fuse associated with said cover to provide timed motion for arming said ball rotor.

6. The combination in claim 5 wherein said centrifugal force responsive means comprises an expandable coil spring surrounding said cover and having one end secured to said cover and a second end secured to said housing.

. The combination in claim 6 wherein said apement means includes a peripheral bevelled in the forward surface of said cover, a plurality of gear teeth formed in said bevel surface, an escapement lever pivotally mounted in a housing and having a rearward surface adjacent to and substantially parallel with the forward surface of said cover, and a plurality of lets on said escapement lever surface intermittently engaging said gear teeth.

A delay arming device for a projectile fuse comprising a housing, an arming ball rotor and housing rotatable from first unarmed position to second armed position, means including rotatable cover for said housing engaging said rotor to rotate the same, and escapement means engaging said cover constructed and arranged to provide time motion for arming said rotor.

10. A delay arming device for fuses for rotatable projectiles comprising a housing symmetrical about a longitudinal axis and having an axial interbore, an arming ball rotor in said interbore rotatable from first unarmed position to second armed position, a pivot pin in said housing extending into a drilled cavity in said rotor to provide an axis of rotation for said rotor normal to said longitudinal axis, said rotor having an arcuate peripheral slot, a cover slidably gaging said housing, a setting pin in said cover extending into said peripheral slot, means to turn said cover relative to said housing whereby said setting pin rotates said ball relative to said cover, said means comprising a power spring coiled about said cover having one end secured to said housing and a second end secured to said cover, said spring being expansible in response to centrifugal force to turn said cover, and capement means in said fuse associated with said cover to provide timed motion for arming said ball rotor.

11. The combination in claim 10 wherein said capement means includes a peripheral bevel formed in the forward surface of said cover, a plurality of gear teeth formed in said beveled surface, an escapement lever pivotally mounted on said fuse and having a rearward surface adjacent to and substantially parallel with the forward surface of said cover, and a plurality of notches on said escapement lever interdentally engaging said gear teeth.

12. A delay arming device for fuses for rotating projectiles comprising a cylindrical housing symmetrical about a longitudinal axis and having an axial counterbore, an arming ball rotor in contiguous relation with the walls of said counterbore rotatable through 90 degrees from first unarmed position to second armed position, said ball rotor having a diametral bore to receive a detonator with an axis normal to said longitudinal axis when said fuse is unarmed and coincident with said longitudinal axis when said fuse is armed, said housing having a pivot pin extending into a drilled cavity in said rotor to provide an axis of rotation for said rotor normal to said longitudinal axis and to said detonator axis, said rotor having an arcuate peripheral slot, a cylindrical cover slidably engaging said housing, a setting pin protruding inwardly from said cover and extending into said arcuate slot, means in response to centrifugal force to rotate

5 said cover relative to said housing about said longitudinal axis whereby said setting pin rotates said ball rotor relative to said cover, said means comprising a coil spring encircling said cover in unarmed position and expansible in response to centrifugal force, said spring having one end secured to said housing and the other end secured to said cover, and escapement means in said fuse adapted to cooperate with said cover to provide
10 timed motion in rotating said ball rotor into armed position.

13. The combination in claim 12 wherein said escapement means comprises a peripheral bevel formed in the forward surface of said cover, an odd number of equally spaced gear teeth distributed about said beveled surface, an escapement lever pivotally mounted in diametrically opposed bearings in said fuse on an axis normal to said longitudinal axis, said lever having a substantially cylindrical central portion with its rear face adjacent to and parallel with the forward face of said cover, a pair of diametrically opposed pallets formed on the rear face of said lever on an axis normal to the axis of pivot of said rotor, each said pallet alternately interdentally engaging said gear teeth as said cover rotates to thereby provide timed motion for arming said ball rotor.

14. A delay arming device for a projectile fuse comprising a housing having an axial counterbore, a cylindrical escapement pawl in said counterbore mounted for rocking motion about an axis normal to the longitudinal axis of said housing, said pawl having an axial substantially cylindrical bore, a cover for said housing having a flange slidably engaging the wall of said counterbore for rotation about the longitudinal axis of said housing, a ball rotor received in the bore of said escapement pawl and pivotally mounted for rotation about an axis normal to the longitudinal axis of said housing and in a plane of motion normal to the plane of motion of said cover, a setting pin integral with said housing and extending into an arcuate peripheral slot in said ball rotor, a pair of semi-spherical pallets diametrically secured on the forward face of said escapement pawl, each alternately perimetrically engaging semi-spherical holes formed concentrically about the longitudinal axis of said cover and on the rearward face of said cover, when said cover turns, and a coil spring having one end connected to said cover and the other end to said housing, responsive to acceleration of said projectile to turn said cover whereby said ball rotor rotates in time motion into arming position.

15. The combination in claim 14 including a diametral bore in said rotor, a detonator in said diametral bore with axis lying crosswise of the longitudinal axis of said housing, when said fuse is unarmed and movable into coincidence with said longitudinal axis to arm said fuse.
